UNITED STATES PATENT OFFICE.

SAMUEL ROBERT OGG, OF NEW YORK, N. Y., ASSIGNOR TO BERNHARD ULMAN & CO., OF SAME PLACE.

DESIGN FOR FABRIC.

SPECIFICATION forming part of Design No. 26,694, dated February 23, 1897.

Application filed January 15, 1897. Serial No. 619,375. Term of patent 3½ years.

To all whom it may concern:

Be it known that I, SAMUEL ROBERT OGG, a citizen of the United States, residing in the city and county of New York, in the State of New York, have invented and produced a new and original Design for Fabric, of which the following is a specification, reference being had to the accompanying drawing, forming a part thereof.

The essential feature of my design consists in a fabric, such, for example, as a spread, cover, or the like, having its face provided with the independent fields differentiated from the face of the fabric and having the form of playing-cards, the said independent fields being provided with symbols, such as are ordinarily placed upon playing-cards.

In the accompanying drawing, A represents the face of the fabric.

B represents the independent fields, shaped like playing-cards, and C, D, E, and F represent, respectively, hearts, clubs, diamonds, and spades, the symbols on the faces of the fields B. The several independent fields are shown as connected by a vine G, made up of connected curved lines, and are arranged around a central field on the fabric.

What I claim is—

The design for a fabric substantially as herein shown and described.

SAMUEL ROBERT OGG.
